(57) **CLAIM**

The ornamental design for a spiral hanger with connectors for suspending aerial wires or cables, as shown and described.

DESCRIPTION

FIG. 1 is a front elevation view of a spiral hanger with connectors for suspending aerial wires or cables showing my new design;

FIG. 2 is a bottom plan view thereof;

FIG. 3 is a top plan view thereof;

FIG. 4 is a rear view thereof;

FIG. 5 is a left side elevational view thereof;

FIG. 6 is a right side elevational view thereof; and,

FIG. 7 is a cross-section view taken along line 7—7 of FIG. 1, thereof.
